US0D1111923S

(12) **United States Design Patent** (10) **Patent No.:** **US D1,111,923 S**
(45) **Date of Patent:** **** Feb. 10, 2026**

(54) **MOTOR VEHICLE AND/OR TOY REPLICA THEREOF**

(71) Applicant: **TOYOTA JIDOSHA KABUSHIKI KAISHA**, Toyota (JP)

(72) Inventors: **Shota Ito**, Antibes (FR); **Hisatoshi Katsukawa**, Yokohama (JP); **Katsuhiro Suzuki**, Shenzhen (CN); **Guangxu Jin**, Shenzhen (CN)

(73) Assignee: **TOYOTA JIDOSHA KABUSHIKI KAISHA**, Toyota (JP)

(**) Term: **15 Years**

(21) Appl. No.: **29/914,039**

(22) Filed: **Oct. 12, 2023**

(30) **Foreign Application Priority Data**

Apr. 14, 2023 (JP) ..... 2023-007775 D

(51) **LOC (15) Cl.** **12-08**

(52) **U.S. Cl.**

USPC **D12/91**

(58) **Field of Classification Search**

USPC D12/85, 86, 87, 88, 89, 90, 91, 92, 98;

D21/433, 434, 533, 535

CPC B62D 25/00; B62D 25/06; B62D 33/00;

B62D 35/00

See application file for complete search history.
